US00D830338S

(12) **United States Design Patent** (10) **Patent No.:** **US D830,338 S**
Yan (45) **Date of Patent:** **** Oct. 9, 2018**

(54) **WIRELESS HEADSET**

(71) **Applicant:** **SHENZHEN FUSHIKE ELECTRONIC CO., LTD**, Shenzhen, Guangdong (CN)

(72) **Inventor:** **Xiaohuang Yan**, Fuzhou (CN)

(73) **Assignee:** **SHENZHEN FUSHIKE ELECTRONIC CO., LTD**, Shenzhen, Guangdong (CN)

(**) **Term:** **15 Years**

(21) **Appl. No.:** **29/606,713**

(22) **Filed:** **Jun. 7, 2017**

(30) **Foreign Application Priority Data**

Mar. 28, 2017 (CN) 2017 3 0094843

(51) **LOC (11) Cl.** **14-01**
(52) **U.S. Cl.**

USPC **D14/206**; D14/226

(58) **Field of Classification Search**
USPC D14/206, 223, 205, 225, 226; D24/174; 181/129, 130, 135; 379/430, 431; 381/380, 381, 382, 370, 375, 322, 330, 381/324, 328, 74; 455/90.3, 575.1, 569.1

CLAIM

The ornamental design for wireless headset, as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof; and,

FIG. 9 is a reference view of the wireless headset in a use state.

The broken lines depict environment that forms no part of the claimed design.

1 Claim, 8 Drawing Sheets
